UNITED STATES PATENT OFFICE

97,569

DESIGN FOR AN INSTRUMENT TABLE

Otto E. Trautmann, Irondequoit, N. Y., assignor
to Bausch & Lomb Optical Company, Roches-
ter, N. Y., a corporation of New York

Application May 28, 1935, Serial No. 57,057

Term of patent 7 years

To all whom it may concern:

Be it known that I, Otto E. Trautmann, a citizen of the United States and a resident of the town of Irondequoit, county of Monroe, and State of New York, have invented a new, original, and ornamental Design for Instrument Tables, of which the following is a specification, reference being had to the accompanying drawing, forming a part thereof.

The figure is a perspective view of an instrument table showing my design.

I claim:

The ornamental design for an instrument table substantially as shown.

OTTO E. TRAUTMANN.
